UNITED STATES PATENT OFFICE

WARREN H. MCLEOD, OF BOULDER, COLORADO

GOLF TEE

Application filed March 18, 1929. Serial No. 348,012.

This invention relates to an improved type of golf tee and its more specific aspect contemplates the provision of a golf tee formed from a homogeneous earthy material in the absence of a binder and so constructed as to be self-sustaining and capable of withstanding handling in shipment and the like but disintegrable upon impact as, for example, when struck by a golf club in play.

10 A preferred form of golf tee is a hollow cylinder which may have one end placed upon the ground and the ball supported upon the opposite end. When such hollow cylinder tees are formed from homogeneous earthy material so as to be disintegrable upon impact by a golf club in play, my experience has demonstrated that the cylinders frequently become cracked and the tees mutilated in shipment and handling before 15 they are used. I have found that if these cylindrical tees formed from homogeneous earthy material so as to be disintegrable are compressed in such manner as to provide a transverse reinforcing web of the homogeneous earthy material, the cylindrical tees are preserved against cracking and mutilation in a very satisfactory manner. It is therefore, the specific purpose of the present invention to provide reinforced, cylindrical 20 golf tees formed from homogeneous earthy material.

The invention will be better understood by reference to the accompanying drawings forming a part hereof, in which

25 Figure 1 is a side elevational view of a cylindrical tee of uniform diameter;

Fig. 2 is a sectional view taken on the line 2—2 of Figure 1;

30 Fig. 3 is a side elevational view of a modified form of the invention, showing a golf tee formed from concentric cylinders having different diameters;

Fig. 4 is a view showing the modified tee of Figure 3 in reverse position and

35 Fig. 5 is a cross sectional view taken on the line 5—5 of Figure 3.

Referring to the drawings the golf tee 1 is cylindrical in form and has the smooth ends 2 and 3. The cylinder is formed by compressing a homogeneous earthy material

such, for example, as a colloidal clay, in a suitable mold. The mold is so formed that the cylinder is provided during the molding operation, with a transverse core or web 4, more particularly shown in Figure 2. The 55 web 4 is, therefore, formed of the same homogeneous material as the walls of the cylinder and is also disintegrable. The web 4, however, functions as a reinforcing member for the walls of the cylinder 1 and guards against 60 premature cracking and mutilation of the tee.

In Figures 3 to 5 a modified form of the invention is illustrated. In accordance with this modified form of tee, the golf tee A is 65 formed from the concentric cylindrical sections B and C, the diameter of the cylindrical section B being less than the diameter of the cylindrical section C. By providing cylindrical sections of different diameters at the opposite ends of the golf tee A, it will be apparent that a golf ball diagrammatically shown at X, will be seated more deeply in the golf tee when the cylindrical section C of greatest diameter is used as the ball supporting surface (as shown in Figure 4) than when the cylindrical section B which is less diameter is employed as the ball supporting surface (as shown in Figure 3). In this modified form of the invention as in the 70 preferred form, the golf tee is so molded as to be provided with a transverse web D 75 functioning to reinforce the walls of the tee.

From the foregoing it will be apparent that the invention permits the production of 80 disintegrable cylindrical golf tees from homogeneous earthy material sufficiently reinforced to prevent premature disintegration of the tees due to handling and shipment.

Having thus described my invention, what 85 I claim is:

1. A golf tee of substantially hollow cylindrical form compressed from a homogeneous earthy material and having formed integral therewith a relatively thin disintegrable 90 transverse reinforcing web.

2. A golf tee comprising hollow cylindrical sections of different diameters, said sections being adapted to be selectively used 95 as a ball supporting surface.

3. A disintegrable golf tee comprising integral hollow cylindrical sections of different diameters and disintegrable means reinforcing said sections.
5. 4. A golf tee having disposed at each end thereof a hollow cylindrical section, the hollow cylindrical section at one end being of less diameter than the hollow cylindrical section at the opposite end.
10. 5. A golf tee having disposed at each end thereof a hollow cylindrical section, the hollow cylindrical section at one end being of less diameter than the hollow cylindrical section at the opposite end, and a transverse web extending across the tee substantially at the point of juncture of said hollow cylindrical sections.
